(57) **CLAIM**

The ornamental design for a combination infant teether and feeder, as shown, and described.

DESCRIPTION

FIG. 1 is a top perspective view of a combination infant teether and feeder showing our new design;
FIG. 2 is a side elevation view thereof;
FIG. 3 is a front elevation view thereof;
FIG. 4 is a rear elevation view thereof;
FIG. 5 is a top plan view thereof;
FIG. 6 is a bottom plan view thereof;
FIG. 7 is a top perspective view of the combination infant teether and feeder, shown exploded for clarity of disclosure;
FIG. 8 is a top perspective view of the combination infant teether and feeder, shown with the cover removed for clarity of disclosure;
FIG. 9 is a side elevation view thereof;
FIG. 10 is a front elevation view thereof;
FIG. 11 is a top plan view thereof; and,
FIG. 12 is a bottom plan view thereof.

1 Claim, 12 Drawing Sheets
